DESIGN FOR A STOVE

Frank T. Herron, Chattanooga, Tenn., assignor to
The American Brake Shoe and Foundry Com-
pany, New York, N. Y., a corporation of Dela-
ware

Application January 30, 1939, Serial No. 82,666

Term of patent 14 years

To all whom it may concern:

Be it known that I, Frank T. Herron, a citizen of the United States, residing at Chattanooga, in the county of Hamilton and State of Tennessee, have invented a new, original, and ornamental Design for a Stove, of which the following is a specification, reference being made to the accompanying drawing, forming a part thereof, in which

Fig. 1 is a perspective view of a stove embodying my new design; and

Fig. 2 is a side elevational view of the same.

The characteristic features of my design reside in the specific stove shown having a two-panel front of the proportions and ornamented in the manner specifically as shown.

I claim:

The ornamental design for a stove, as shown and described.

FRANK T. HERRON,
